UNITED STATES PATENT OFFICE.

CARL H. MENGEDOHT, OF SEATTLE, WASHINGTON.

DOOR-OPENER.

1,269,545.

Specification of Letters Patent. Patented June 11, 1918.

Application filed May 21, 1917. Serial No. 170,054.

To all whom it may concern:

Be it known that I, CARL H. MENGEDOHT, a citizen of the United States, residing at Seattle, in the county of King and State 5 of Washington, have invented certain new and useful Improvements in Door-Openers; and I do hereby declare the following to be a full, clear, and exact description of the invention, such as will enable others skilled 10 in the art to which it appertains to make and use the same.

This invention relates to closure operators, and more particularly to an electro-magnetic apparatus for opening doors, especially the 15 ordinary hingedly mounted doors.

It is one of the objects of the present invention to provide an apparatus for opening a swinging door, and further to provide an electro-magnetic apparatus in which there is 20 arranged a control or circuit closure which is adapted to be actuated by a person when it is desired to secure the opening of the door.

A further object of the invention is to 25 provide a simple, practical and reliable electro-magnetic device so arranged that it may be disposed conveniently with relation to a fixed support and to the swinging door and to provide connections between the actuating 30 device and the door.

It is a further object of the present invention to provide a solenoid apparatus for opening a door and to provide means for 35 opening the door through the actuation of the solenoid core when the solenoid is energized.

The invention consists of the combination 40 of a suitably supported door of an electro-magnetic device, its circuit, and a suitable circuit closing apparatus, and especially consists in the present adaptation of an oscillating solenoid and the connections therebetween and the swinging door.

With the above objects in view and others 45 as will be rendered manifest in the following specification there is shown in the accompanying drawing and described in the following specification one embodiment of the invention, in which drawing:

50 Figure 1 is a plan view of the apparatus showing the parts in position with the door closed.

Fig. 2 is a plan view showing the parts with the door swung open.

55 Fig. 3 is a sectional view showing the

arrangement of one form of circuit controlling device for the apparatus.

The invention as herein illustrated comprehends the provision of means for operating a swinging door, a portion of which is 60 shown at 2 which is hingedly connected at 3 to any suitable fixed structure as, for instance, a wall or the jamb 4 of the door. The door opening device is illustrated as comprising a solenoid coil 5 having a suitable core 6 which latter in the present organization is shown as pivotally connected at 7 by means of a link 8 to a lever 9 which is fulcrumed at 10 upon a suitable bracket or other bearing 11 which may be appropriately attached to the fixed wall or jamb 4. The lever 9 projects from its pivot 10 and is bifurcated at its end as at 9' to receive a pin 12 or other suitable connecting element, which, as here shown, is mounted 75 upon a bracket 13 attached to the face of the door 2. The end of the link 8 is connected at the pivot point 8' to the lever 9 intermediate the length thereof between the pivot 10 and the bifurcated end 9'. 80

For the purpose of controlling the arc of the swinging link 8 and securing the mechanism efficiently in the application of the force derived from the excitation of the solenoid 5, I prefer to use a guide or guard 85 of suitable type which in the present instance is shown as a forked lever 14 which is pivoted on the fulcrum 10 of the lever 9 and in the slot of the fork the pin 7 connecting the solenoid rod to the link 8 is 90 adapted to reciprocate during the operation of the device. It is one of the important features of the present invention to so mount the solenoid and its operating links that a minimum amount of oscillation or 95 swinging movement of the solenoid may be provided for and secure, and in its present arrangement this solenoid is shown as mounted in a bearing 5' which is pivoted adjacent one end at 5^a upon a suitable support, as, for instance, the bracket or hanger 11 which is provided to receive the fulcrum 10. The fulcrum 5^a of the solenoid bearing 5' is disposed adjacent one end of the bearing as shown in Figs. 1 and 2, and thus when 100 the coil is electrically excited and its core 6 drawn inwardly the action will be through the core 6 and its connecting link 8 to swing the lever 9 which stands approximately at an angle of 45 degrees to the plane of the 110

door and wall, as shown in Fig. 1, the movement of the arm 9 in opening the door to the position shown in Fig. 2 being through an arc of about 90 degrees during which action the fulcrum or connecting pin 7 slides outwardly through the forked lever 14 to the position shown in Fig. 2 at which time the solenoid is swung slightly downwardly on its fulcrum 5^a and the fork 14 and the door operating rod 9 are caused to swing at varying relations on the pivot 10 and the link 8 is brought into substantial alinement with the axis of the solenoid core 6. When the solenoid is deenergized the door 2 may be closed by any suitable force, and it will be seen that the link 8 and the lever 9 are controlled so as to prevent the idle movement of the link 8 on its pivotal connection 8' of the rod 9 through the instrumentality 20 of the controlling forked lever 14.

Any suitable source of electrical energy may be utilized for exciting the solenoid coil, as, for instance, either a battery circuit or a lighting circuit, the lead-in wires which are 25 shown at 15 and 16 being connected to the terminals of the coil, the wire 16 passing preferably through a suitable flexible connection to the door 2 as shown in Fig. 2, and upon which door there is adapted to be 30 provided any suitable form of circuit making or breaking apparatus which may be operated by a person desiring to have the door opened.

A simple form of the circuit closing apparatus is shown in Fig. 3, in which the lead-in wire 16, for instance, is connected to a suitable contact 17 adapted to be engaged by a movable circuit closing or contact member 18 which preferably is adapted 40 to be automatically moved to circuit-breaking position in any suitable manner, as by means of a spring 19. The movable circuit closer 18 may be actuated through a simple mechanism comprising preferably manually 45 operable latches 20, one disposed on each side of the door and conveniently disposed with relation to the grips or handles 21 provided on the door, although it is to be understood that any suitable and convenient 50 and preferred form of device for controlling the operation of the circuit closing contact may be utilized. When the circuit is closed by the contact 19 current flows through a lead wire 22 connected thereto and which is 55 led from the door through any suitable form of flexible connection to provide for the swinging or hinging movement of the door to be connected to the source of supply.

For the purpose of preventing the door 60 from opening too rapidly under the impulse of the force created by the excitation of the solenoid coil, a suitable retarding or checking means may be employed. A simple form of controlling device for preventing the too 65 rapid opening of the door may be incorpo-

rated in the form of a dash-pot which may be suitably arranged with relation to the operating mechanism, and as shown may be formed as a portion of the solenoid coil by attaching thereto a cylinder or receptacle 70 23 which is closed at one end and into which the adjacent end of the solenoid core is adapted to move when the coil is excited, the compressed air in the cylinder 23 serving as a cushion, and thereby retarding the accelerated movement of the door. To provide for free closing movement of the door without substantial resistance from the dash-pot, the latter may be provided with an inwardly 75 opening check valve 24 shown in the form 80 of a flat spring to eliminate suction resistance at the dash-pot as the solenoid coil is drawn forwardly again by the closing of the door. Sufficient relief of air under pressure from within the dash-pot 23 may be 85 secured by the escape of air around the surface of the core 6 within the bore of the solenoid 5, or in any other suitable manner as may be desired.

From the foregoing it will be seen that 90 I have provided a simple, practicable, inexpensive and efficient device for controlling the opening of a door, and one in which the parts are so organized and arranged that they may be readily renewed and replaced 95 and to which access may be freely had for the purpose of adjustment or renewal when necessary, and it is understood that various modifications in the arrangement, construction and details of the various parts may be 100 resorted to within the scope of my invention and limits of the appended claims.

What is claimed as new is:

1. A closure operating apparatus including a closure to be operated, a support on 105 which it is movably mounted, and electro-magnetic means for opening said closure, including a pivoted solenoid and its core connected to the said closure and the support, and a guide, independent of the connection 110 between the door and means, for controlling the swinging of the solenoid.

2. A closure operating apparatus including a closure to be operated, a support on 115 which it is movably mounted, and electro-magnetic means for opening said closure, including a pivoted solenoid and its core connected to the said closure and the support, and a guide co-acting with the core to control the solenoid movement.

3. A closure operating apparatus including a closure, a fixed support upon which it is movably mounted, and electro-magnetic means for actuating the closure comprising a pivoted solenoid coil attached to one thereof and its core attached to the other, and levers swinging on a common fulcrum, one controlling the solenoid and the other connecting the core and closure.

4. A closure operating apparatus includ-

- ing a closure, a fixed support upon which it is movably mounted, electro-magnetic means for actuating the closure comprising a solenoid coil attached to one thereof and its core attached to the other, and means for controlling the speed of the opening movement of the closure under the impulse of the solenoid comprising a dash-pot in which the core works.
- 5 10. 5. The combination with a door, and a support upon which it is hinged, of a solenoid coil having articulated connection with one thereof, and a core for the solenoid having articulated connection with the other by a lever pivoted to the support and to the door, and an independent lever connected to the core for directing the movement of the solenoid.
- 15 6. The combination with a door and a support to which it is hinged, of a pivoted solenoid carried by one thereof and having a core movably connected to the door and a lever for controlling the angle of oscillation of the solenoid, connected to said core.
- 20 7. The combination with a door and a support to which it is hinged, of a pivoted solenoid carried by one thereof and having a core movably connected to the other, and a
- 25 circuit for the solenoid including circuit making and breaking devices, the solenoid 30 chamber closed at one end to form an air cushion for the core.
- 30 8. A device for opening a hinged door, comprising a solenoid pivotally mounted with relation to the door and having a core 35 operatively and pivotally connected to the door whereby when the solenoid is energized said door is opened, and pneumatic means for controlling the core movement, the core forming a piston for said means.
- 35 9. A device for automatically opening a hinged door, comprising a pivoted solenoid on a fixed support, a motion controlling member for the solenoid, a core therein, and connecting means between said core and the door including a lever engaging a part on the door, and a link connecting the lever and solenoid core.
- 40 10. A device for automatically opening a hinged door, comprising a pivoted solenoid on a fixed support, a core therein, and a dash pot carried by the solenoid and in which the core moves.
- 45 In testimony whereof I affix my signature.
- 50

CARL H. MENGEDOHT.
